UNITED STATES PATENT OFFICE

HARRY H. KNIGHT, OF DALLAS, TEXAS, ASSIGNOR TO DALLAS ENGINEERING CORPORATION, OF DALLAS, TEXAS, A CORPORATION OF TEXAS

DESIGN FOR A FAN

Application filed April 20, 1931. Serial No. 39,575. Term of patent 14 years.

To all whom it may concern:

Be it known that I, HARRY H. KNIGHT, a citizen of the United States, residing at 1115 Hall Street, Dallas, in the county of Dallas and State of Texas, have invented a new, original, and ornamental Design for Fans, of which the following is a specification, reference being had to the accompanying drawings, forming part thereof.

Figure 1 is a plan view of a fan, showing my new design,

Figure 2 is a side elevation of the same, and Figure 3 is a front elevation.

I claim:

The ornamental design for a fan, substantially as shown.

In testimony whereof I affix my signature.

HARRY H. KNIGHT.
